WINDOW SASH BALANCE

Elmer A. Anderson, Moorhead, Minn.

Application January 11, 1935, Serial No. 1,405

7 Claims. (Cl. 16—195)

This invention relates to windows, and more particularly to a means for facilitating the opening of either the bottom or top sash individually, or the simultaneous opening and closing of the upper and lower sashes of the window through the manipulation of a novel controlling means.

Another object of this invention is the production of a simple and efficient sash opening mechanism for windows which may be so adjusted as to permit the opening of the bottom and top sashes individually if desired, or the simultaneous opening and closing of the top and bottom sashes.

A still further object of this invention is the production of a simple and efficient latching means which may be so operated as to quickly and efficiently permit of the individual or the simultaneous operation of the window sashes.

Other objects and advantages of the present invention will appear throughout the following specification and claims.

In the drawings:

Figure 1 is a front elevation of a window frame showing the sashes in a closed position;

Figure 2 is a front elevation of a window frame showing the upper sash in a partly open position;

Figure 3 is a front elevation of a window frame showing the lower sash in a partly open position;

Figure 4 is a front elevation of a window frame showing both the upper and the lower sashes in a partly open position;

Figure 5 is an enlarged vertical sectional view through a portion of a window frame showing the novel sash operating mechanism, the top and bottom sashes being closed;

Figure 6 is a vertical sectional view through a portion of the window frame showing the top and bottom sashes partly open;

Figure 7 is an enlarged fragmentary vertical sectional view showing the latching bolt;

Figure 8 is an enlarged vertical sectional view through the window frame showing the sashes in a second adjusted position;

Figure 9 is an enlarged sectional view taken on line 9—9 of Figure 5;

Figure 10 is an enlarged section taken on line 10—10 of Figure 1;

Figure 11 is a front elevation of one of the socket plates carried by the lower sash;

Figure 12 is a perspective view of the operating button carried by the lower sash;

Figure 13 is a plan view showing the outer face of the bottom sash;

Figure 14 is a plan view showing the inside face of the top sash; and

Figure 15 is a vertical section through a portion of the window frame illustrating the bottom sash and a portion of the upper sash and the arrangement of the stop plates for limiting the movement of the sashes.

By referring to the drawings, it will be seen that 10 designates the conventional window frame within which is slidably mounted an upper sash 11 and a lower sash 12, which sashes are of conventional type having added thereto certain novel mechanical structure for controlling the operation of the sashes. The upper and lower sashes are arranged in spaced relation in 15 the conventional manner and upon the frame, and between these upper and lower sashes 11 and 12, at the point of approximate overlap, is arranged a pinion supporting casing 13 within which is journaled a pinion 14, the pinion 14 being carried by the shaft 15 and rotating therewith. The shaft 15 may be journaled in any suitable or desired manner within the window frame 10.

The upper sash 11 is provided along each longitudinal inner edge with a channel 16 in which is mounted a rack bar 17, the rack bar 17 having rack teeth 18 upon its inner face for meshing with the pinion 14, as shown in Figure 5. The rack bar 17 may be anchored in position 20 by means of suitable securing screws 19.

The lower sash 12 is provided with channels 20 upon either side of the sash along the inner face thereof, as shown in Figure 8, and slidably mounted rack bars 21 are carried within these channels 20. These rack bars 21 are provided with rack teeth 22 upon their inner faces, as shown in Figures 5 and 8, which rack teeth 22 mesh with the pinion 14, as shown in Figures 5, 6 and 8. Each rack bar 21 is provided with a 30 pair of longitudinally extending slots 23, which slots 23 are elongated and receive the securing screws 24, the screws having enlarged heads 25 which fit within the channels 26, the channels 26 constituting a trackway for the heads 25 and 35 permitting the screws 24 to hold the racks against accidental displacement. The screws 24 will limit the longitudinal movement of the rack bar 21 relative to the sash 12.

The rack bar 21 is provided with a depending 40 tongue 27, which depending tongue 27 fits within the bifurcated end 28 of a dog 29, the dog 29 being pivotally secured to the tongue 27 by means of the pivot pin 30. The dog 29 is provided with a rearwardly extending bulged portion 33 which 45

tongue 27, which depending tongue 27 fits within the bifurcated end 28 of a dog 29, the dog 29 being pivotally secured to the tongue 27 by means of the pivot pin 30. The dog 29 is provided with a rearwardly extending bulged portion 33 which 50

is adapted to normally rest within a pocket or channel 34 formed in the sash 12, as shown in Figure 5. A flat spring 35 is adapted to engage the rear face of the dog 29 and to normally urge the same to a forward swinging position to move the front edge of the dog to an extended position, such as is shown in full lines in Figure 6. The dog 29 is provided with a bolt receiving socket 36, as shown in Figure 7 in order to permit the dog 29 to be firmly held in a retracted or inactive position.

The sash 12, upon either side thereof near its bottom, is provided with a socket 37 in which is slidably mounted a spring pressed bolt 32, the reduced shank portion 38 of the bolt carrying a coil spring 39 and extending through the guides 40. A suitable guiding casing 41 is carried by the outer end of the socket 37 through which the head portion of the bolt 32 extends. The head portion of the bolt 32 is preferably beveled, as at 42, so as to facilitate the riding of the dog 29 over the outer end of the bolt 32 when the rack bar 21 is moved downwardly to an anchored position.

The window frame 10 may support in any suitable or desired position, a pair of latching plates 43 and 31, preferably located at a point in longitudinal alignment with the pinion 14. These latching plates 43 and 31 are provided with inclined sockets 44 and 44a respectively, the socket 44 having a stop shoulder 44b at its upper end and the socket 44a having a stop shoulder 44c at its lower end. When the sash 12 is raised to the position shown in full lines in Figure 8 and the bolt 32 has been withdrawn from the dog 29, the spring 35 will force the dog 29 to the position to engage the stop shoulder 44c when the bottom sash is raised to this position. This operation will also move the upper sash 11 downwardly to the position shown in Figure 8. The bottom sash 12 may now slide downwardly independently of the rack bar 21 to a closed position due to the fact that the dog 29 will be in engagement with the shoulder 44c and the rack bar 21 will be held against sliding movement.

In order that the bolt 32 may be properly and manually operated to move the same to a retracted position, an operating plate 45 engages the shank portion 38 of the bolt 32 thereby permitting the bolt to be manually shifted from a locking to an unlocked position. The plate 45 is provided with a finger lug 46 and this plate 45 preferably covers the slot 47 formed in the socket plate 48 through which the connecting pin 50 of the plate 45 extends. The pin 50 engages the shank portion 38 previously described.

The sash 12 is provided with lift sockets 51 within which sockets are mounted the socket plates 48 previously mentioned, the plate 45 and finger lug 46 being normally shielded within the socket plates 48, as shown in Figure 10.

Should it be desired, suitable stop plates 52 may be fitted upon the window frame 10 by fitting within suitable notches 53 to limit the upward movement of the lower sash 12. A stop plate 54 may also be carried by the frame 10 to constitute a means for limiting the downward movement of the top sash 11, the plate 54 being held in position through the medium of the securing screw 55—see Figure 15.

The operation of the device is as follows:—

When the parts are in the position shown in Figure 5, the top and bottom sashes 11 and 12 are closed. The bolts 32 which are carried upon either side of the bottom sash, as will be obvious

by considering Figures 1 to 4, inclusive, will engage the dogs 29 and hold these dogs in a retracted position, such as is shown in Figure 5, the dogs 29 resting upon the rest plates 56 carried by the frame 10. It is now possible to automatically lower the upper sash 11 merely by raising the lower sash 12 due to the fact that since the rack 21 is locked for movement with the lower sash 12, this rack 21 will mesh with the pinion 14 and cause the rack 17 to be moved downwardly, the rack 17 being carried by the upper sash 11. The reverse movement will cause both sashes to simultaneously close.

Should it be desired to open the upper sash and also the lower sash, the operation of the parts would be as follows: The bolts 32 are moved to a position for engagement with the dogs 29 locking the racks 21 in engagement with the lower sash 12. The lower sash is then raised and as the racks 21 move with it the pinions 14 will be rotated and since they mesh with the racks 17, the upper sash 11 will be lowered an equal extent, such as is shown in Figure 8. By moving the bolts 32 out of engagement with the dogs 29 and allowing the dogs 29 to engage the stop shoulders 44c of the upper plates 31, the rack bars 21 will be secured against downward movement, as shown in Figure 8, and the lower sash 12 may then be moved downwardly in the direction of the dotted arrow in Figure 8 to close the lower sash and leave the upper sash open. During this movement the pins 24 slide in the slots 23, the rack bars 21 and pin 14 remaining stationary. When it is desired to cause the bolts 32 to again engage the sockets 36 of the dogs 29, it is only necessary to raise the lower sash to a position in which the dogs will be shifted by cam action of the edges 44a of the plates 31 to a position in which the spring pressed bolts 32 will immediately fit within the sockets 36. The lower sash may then be slid downwardly to a closed position and rotation of the pinions will cause the upper sash to simultaneously move upwardly to a closed position.

When it is desired to close the top sash and move the bottom sash to an open position independently of the upper sash, the bottom sash is raised to the point where the dogs 29 engage the stop shoulder 44b and the bolts 32 are released from the dogs 29. The racks 21 will then lock against their upward movement. This movement of the lower sash naturally will move the upper sash slightly to a lowered position. However, as the bottom sash 12 is moved upwardly after the dogs have engaged the shoulders 44b, the bolts 32 will enter the notches 57 formed in the rack bars 21 and located above the dogs 29 and a slightly downward movement of the bottom sash will cause the racks 21 to move downwardly and the racks 17 will be moved upwardly by rotation of the pinions, thus closing the top sash. The bolts 32 may then be withdrawn from engagement with the dogs 29 and the lower sash moved upwardly to the desired open position.

When the two sashes are to be simultaneously moved, the rack bars 21 are locked in a stationary position by means of the bolts 32 which engage the dogs 29 in the manner as illustrated.

It will be noted that when the stop plates 53 and 54 are used the sashes may be limited in their movement through the structure provided, a person cannot fall out through the window opening, and neither can entrance be made through the window due to the limited amount of space provided by the opening of the sashes.

It should be understood that certain detail

changes in the mechanical construction may be employed without departing from the spirit of the invention so long as these changes fall within the scope of the appended claims.

5 Having described the invention, what I claim as new is:—

1. In a device of the character described, a sash, a movable rack bar carried by said sash, a dog for holding said rack bar in a set position pivotally secured to the lower end of the movable rack bar, the dog being adapted for engagement by a fastener whereby the rack bar may be held in a set position upon said sash, said sash having a channel formed adjacent the dog, and the dog having a bulged portion fitting in the channel for allowing the rack bar to slide upon the sash, and spring means for normally urging the dog to a latching position.

2. In a device of the character described, a rack bar adapted to be slidably mounted upon a sash, a dog carried by said rack bar and movable into and out of position for locking the rack bar in one position relative to a sash, and said rack bar having additional means whereby it may be locked in another position relative to the sash.

3. In a structure of the character described, a rack bar having a slot formed longitudinally thereof whereby the rack bar may be applied to a sash and slid longitudinally thereof, a dog pivotally connected with the lower end of said rack bar and depending therefrom, and a spring carried by the rack bar and engaging the dog to yieldably hold the dog in a latching position, the dog and rack bar being each formed with a socket for receiving a fastener whereby they may be selectively held in set positions.

4. A window sash actuating means for use with a plurality of window sashes, and a support for said sashes, comprising a rack bar carried by one sash and anchored thereon, a movable rack bar carried by the other sash, a pinion intermeshing between the rack bars of the respective sashes, said movable rack bar being longitudinally slotted to permit limited longitudinal movement thereof with respect to its supporting sash, a dog carried by the slotted rack bar for holding the same against movement in one direction and permitting free sliding of the last mentioned sash with respect to the slotted rack bar, and securing means carried by the last mentioned sash and selectively engageable with the slotted rack bar for securing the same in a set position with respect to the last mentioned sash and with the dog for securing the same in set positions.

5. A device of the class described for use with a plurality of sashes, and a support for the sashes, comprising a fixed rack bar carried by one sash, a longitudinally movable rack bar carried by the other sash, a pinion interposed between the rack bars of the respective sashes, the movable rack bar being longitudinally slotted, a securing pin carried by the second mentioned sash and engaging said longitudinally slotted rack bar for limiting the longitudinal movement of said movable rack bar, a locking dog carried by the movable rack bar for locking the movable rack bar against movement in one direction and at the same time permitting the movement of the last mentioned sash with respect to the movable rack bar, and a releasable bolt carried by the second mentioned sash and engageable with said dog for locking said movable rack bar upon the second mentioned sash for bodily movement with the last mentioned sash, the releasable means being also directly engageable with the movable rack bar for securing the rack bar stationary with respect to said other sash.

6. A device of the class described for use with upper and lower sashes, and a support for the sashes, comprising a rack bar fixedly carried by the upper sash, a movable rack bar carried by the lower sash, a pinion carried by the support between the rack bars of the respective sashes, a dog pivotally secured to the lower end of the movable rack bar, means carried by the support for engaging the dog and holding the movable rack bar against movement in one direction, and a spring operated locking plunger engageable with the dog for moving the dog to an unlocked position and anchoring the movable rack bar upon its supporting sash.

7. In a structure of the character described for use with a support and a sash, a movable rack bar carried by said sash, a dog pivotally secured to the lower end of said rack bar for holding the movable rack bar against movement in one direction, a locking plunger engageable with the dog for holding the dog in an unlocked position and anchoring the movable rack bar upon its supporting sash, said sash having a channel formed adjacent said dog and the dog having a bulged portion fitting in the channel, spring means for normally urging the dog to a latching position, said locking plunger having a beveled outer end to facilitate the riding of the dog over the outer end of said plunger, and a spring yieldably holding said locking plunger in position to automatically engage said dog.

ELMER A. ANDERSON.
